A. L. WILSON

RADIO CONTROL SYSTEM

Filed April 1, 1921

UNITED STATES PATENT OFFICE.

ARTHUR LESLIE WILSON, OF EDGEWOOD, PENNSYLVANIA, ASSIGNOR TO WESTINGHOUSE ELECTRIC & MANUFACTURING COMPANY, A CORPORATION OF PENNSYLVANIA.

RADIO CONTROL SYSTEM.

Application filed April 1, 1921. Serial No. 457,870.

To all whom it may concern:

Be it known that I, ARTHUR LESLIE WILSON, a subject of the King of Great Britain, and a resident of Edgewood, in the county 5 of Allegheny and State of Pennsylvania, have invented a new and useful Improvement in Radio Control Systems, of which the following is a specification.

My invention relates to systems of control 10 and more especially to remote-control systems which are adapted to be operated by radiant energy.

One object of my invention is to provide 15 a remote control system whereby an electro-magnet switch or a relay may be controlled from a distant point by means of electro-magnetic waves.

Another object of my invention is to provide 20 a remote-control system which is highly selective, said system being practically immune from interfering signals.

In the present state of the art, remote-control systems, the operation of which is effected by means of radiant energy, may be 25 divided into two classes: namely, those in which a single impulse controls a single relay, the latter controlling, in turn, means for selecting a desired circuit; and those in which a specific type of impulse and a separate 30 rate receiver and relay are employed for each circuit to be controlled.

A disadvantage, however, of the present radio, remote-control systems is the poor selectivity that may be obtained from interfering 35 signals.

According to my invention, I provide a remote-control system which may be readily operated by the radiant energy from a wireless transmission system and which practically 40 overcomes the difficulties heretofore encountered in providing protection from interfering signals.

The desired result may be accomplished by employing means for transmitting, progressively, predetermined sequences of signals at various wave lengths, and by further employing a receiving system which is selectively responsive to only such signals as are radiated by the transmitting means.

Other objects, as well as details of construction, whereby my invention may be car-

ried out, will be apparent from the following description, taken in connection with the accompanying drawings, in which:

Fig. 1 is a diagrammatic view of a transmitting station embodying my invention. 55

Fig. 2 is a similar view of the receiving station.

Referring to Fig. 1, I have shown a source of energy 1 connected to a primary winding 2 of a transformer 3 through a contactor 4 and a reactor 5. A secondary winding 6 of the transformer 3, which has its opposite terminals shunted by a spark gap 7, is connected by conductors 8 and 9, respectively, to one terminal of a coupling coil 11, and to a distributing switch arm 12 of a switching device 13.

The switching device 13 and a switching device 14, which are similar in structure and are mounted upon a common shaft 15, comprise, respectively, distributing switch arms 12 and 16 and stationary contact members 17, 18, 19 and 21, 22, 23. The stationary contact members 17, 18 and 19 of the switching device 13 are connected by conductors 24, 25 and 26, respectively, to successively increase the effective inductance of the coupling coil 11 by including portions 24^a, 25^a and 26^a thereof in a primary oscillating circuit which includes, in addition, the spark gap 7 and a condenser 27. 70

The stationary contact members 21, 22 and 23 of the switch 14 are similarly connected by conductors 28, 29 and 31, respectively, to successively increase the effective inductance of a coupling coil 32 by including portions 33, 34 and 35 thereof in a secondary oscillatory circuit or antenna circuit which may include, in addition, a ground conductor 36 and an antenna 37. 75

A motor 38, which may be connected to a source of energy (not shown) through a two-point switch 39 and a switch 41, is operatively connected to a shaft 42 through a reduction gear mechanism (not shown) of well known form. The shaft 42 has rigidly secured thereto a worm wheel 43 for engaging a gear wheel 44 to effect the operation of the switch 41, a circuit interrupter or wave-changing switch 45 for effecting the operation of the wave-changing switches 13 80

and 14, and a circuit interrupter or message wheel 46 for operating the contactor 4.

The wave-changing switch or circuit interrupter 45 is provided with a number of commutator segments, according to the desired number of wave changes in the predetermined sequence of signals that is to be radiated. In the drawing, I have shown such a device as provided with three commutator segments, namely; 47, 48 and 49.

An electromagnet 51, the actuating winding of which is controlled by the wave-changing switch 45, effects the rotation of the shaft 15 supporting the switch arms 16 and 17 through a pawl-and-ratchet device, the pawl 52 being attached to an armature member 53 of the relay 51 and the ratchet 54 being attached to the shaft 15. The circuit, which comprises the actuating winding 20 of the relay 51, includes, in addition, the wave-changing switch 45 and a source of energy 55.

The supply circuit of the transformer 3 may be periodically interrupted by means of 25 the message wheel 46 which controls the actuating winding of the contactor 4. The circuit, which includes the actuating winding of the contactor 4 and the message wheel 46, may be energized by means of a source 30 of energy 56. It is, of course, understood that any number of commutator segments may be employed in the message wheel 46, all as determined by the desired sequence of signals that is to be radiated on the wave 35 lengths, as fixed by the wave-changing switch 45.

The switch 41 comprises a stationary member 57 and a rotating switch arm 58. The switch arm 58, which is mounted on a 40 shaft 59 that is actuated by the worm wheel 43 and a gear wheel 44, moves from engagement with a stationary contact member 60 to engagement with a stationary contact member 61 for one complete revolution of the 45 message wheel 46. The stationary contact members 60 and 61 of the stationary member 57 are connected, respectively, to a stationary contact member 63 and 64 of the switch 39. The stationary contact members 59 60 and 61 are insulated from one another by means of insulating material which is placed between the contact members.

Referring to Fig. 2, I have shown a simple receiving circuit which effects the operation 55 of a relay 65 controlling a power circuit 66 only upon the receipt of such signals as are radiated from the transmitting station of Fig. 1. An antenna circuit comprises the antenna 37, tuning coils 67, 68 and 69, the 60 wave-changing switch 13 for varying the tuning of the antenna circuit to correspond to that of the energy radiated from the transmitting station, and a ground conductor 71.

65 A three-electrode vacuum tube, which

comprises a hot cathode 72, a grid 73 and a plate 74, has its grid connected to the antenna circuit by means of a conductor 75 through a condenser 76 and a grid leak 77, the grid leak 77 being connected in shunt 70 relation to the condenser 76. The hot cathode 72, which may be energized by means of a source of energy 78 through a resistor 79, is connected by a conductor 81 to one terminal of the switch member 17. A 75 plate-filament circuit includes therein an actuating winding of a relay 82, a message wheel 83, which is exactly similar to the one at the transmitting station, and a source of energy 84.

80 A wave-changing switch 85, the message wheel 83 and a circuit interrupting device 86 are rigidly secured to a shaft 87, operation of which may be effected by a clockwork mechanism 89 upon engagement of friction discs 91 and 92. The frictional disc 92 may be continuously rotated by the clockwork mechanism 89. The frictional disc 91, which is so mounted upon the shaft 87 as to admit of axial motion, may be operated into engagement with the disc 92 by means of an armature member 93 of the relay 94 upon the energization of the actuating winding 85 of the relay.

85 The operation of the relay 94 may be controlled by means of the circuit interrupter 86 or the relay 82, both of which are connected in parallel in a circuit which includes the actuating winding of the relay 94 and a 90 source of energy 95. The circuit-interrupting device 86 is an exact counter-part of the message wheel 83 with the exception that the conducting portions thereof are slightly raised beyond the mean circumference of the wheel. A pivotally mounted conducting member 96, which has secured thereto a 95 non-conducting member 97, is so disposed that the circuit through the interrupting device 96 is completed only for counter-clockwise rotation thereof. Operation of the 100 switching device 13 may be effected through a pawl-and-ratchet mechanism, as shown in Fig. 1.

105 It is understood, of course, that, while I have shown particular means for actuating the shafts 15 and 87 at the sending and receiving stations, respectively, my invention is not to be limited thereby, other 110 sources of energy being equally applicable.

115 The operation of the main contactor 65 of Fig. 2, which controls the outgoing circuit 66, is effected only upon the engagement 120 of a movable contact member 98, which is secured to the message wheel 83, with the stationary contact member 99. It will be noted that, in the present system, one complete revolution of the message wheel 83 is necessary to effect the operation of the 125 contactor 65. The contact members 98 and 99, just mentioned are included in a circuit 130

which also includes a source of energy 101 and an actuating winding of the contactor 65.

The movement of the message wheel 83 is in such direction that energy is stored 5 in a spring 102, thereby permitting the message wheel 83, the wave-changing switch 85, and the circuit interrupting device 86 to be returned to their initial positions upon one complete revolution therefore 10 of, or upon interruptions in the sequence of signals other than those determined by the transmitting station.

Referring to Fig. 1, and assuming an arrangement of circuits as indicated, it 15 will be noted that energy is being radiated by the transmitting station at a wave length corresponding to the period of the primary oscillating circuit which includes the spark gap 7, the condenser 27 and portion 24 of 20 the coupling coil 11.

Furthermore, it will be noted that a brush 102^a is engaging a conducting segment of the message wheel 46, thereby completing a circuit which includes the source 25 of energy 56, the commutator device or message wheel 46 and the actuating winding of the contactor 4. The actuating winding of the relay 51 is also closed by the engagement of a brush 102 and the conducting 30 segment 47 of the wave-changing switch 45, thereby causing the pawl 52 to be in its forward position, as indicated in the drawing. The switch arms 12 and 16 have been shown as engaging the stationary contact 35 members 17 and 21, respectively, thereby rendering effective portions 24 and 33 of the tuning coils 11 and 32, in their respective circuits.

Upon actuating the switch arm of the 40 two-point switch 39 into engagement with stationary contact member 63, a circuit is completed which extends from conductor 103, through the switch 39, the stationary contact member 60 of the switch 41, the rotation switch arm 58, the shaft 59 and motor 38, to conductor 104, conductors 103 and 104 being connected to a source of energy (not shown). The motor 38 then operates to turn the message wheel 46, the wave-changing switch 45 and worm wheel 43 through one complete revolution. The value of the gear reduction in the worm-wheel mechanism shown is such that the switch arm 58 is moved from engagement 45 with stationary contact member 60 to engagement with the stationary contact member 61 upon one complete rotation of the shaft 42. When the switch arm 58 is actuated out of engagement with the stationary contact member 60, the supply circuit to the motor 38 is interrupted, thereby 50 rendering the motor 4 ineffective.

Upon the successive engagements of the 55 conducting segments 49 and 48 of the wave-changing switch 45 with the brush 102, the

switch arms 16 and 17 of the switches 13 and 14 are further actuated to include, successively, in addition, portions 25, 26 and 34, 35 of the coupling coils 11 and 32, respectively, in their respective circuits, 70 thereby progressively changing the wave length of the energy radiated. Thus, during the time interval in which the message wheel 46 and the wave-changing switch 45 are moving through the arcs 49—47, 48—49 75 and 47—48, successively, signal trains having predetermined characteristics, as determined by the message wheel 46 are being radiated at progressively increasing wave-lengths. 80

As hereinbefore stated, upon a complete rotation of the shaft 42, the circuit of motor 4 is opened, the message wheel 46 having returned to its initial position.

Referring to Fig. 2, assuming the receiving system to be resonant to energy radiated by the transmitting station of Fig. 1, and assuming the apparatus in the positions indicated upon the receipt of signals; variable currents are caused to traverse the plate-filament circuit, thereby effecting the operation of the relay 82. Upon the closing of the relay 82, a circuit is completed which extends from one terminal of the source of energy 95 through the actuating winding 91 of the relay 94 and relay 82 to an opposite terminal of the source of energy 95. The effect of energizing the actuating winding of the relay 94 is to cause the friction disc 91 to be actuated into engagement with the friction disc 92, the latter being continuously rotated by the clock mechanism 89. The clock mechanism 89 then effects the rotation of the switching device 86, the message wheel 83 and the wave-changing switch 85. 95 100

Assuming the signals to arrive at the receiving system according to the sequence determined by the transmitting station, it will be noted that the actuating winding of relay 94 is energized by the operation of relay 82 during the dot-and-dash or signaling periods, and by the operation of the circuit interrupter 86 during the space intervals between the dot-and-dash or non-signaling periods to admit of a complete rotation of the message wheel 83. 110 115

If, however, signals are received at intervals other than those determined by the transmitting station, the actuating winding of the relay 94 is opened, thereby causing the disengagement of the clutch members 91 and 92 and permitting the wave-changing switch 85, the message wheel 83 and the circuit interrupter 86 to return to their initial 120 125 positions.

The advantage of my invention is in the provision of a system of control, which may be employed in connection with any of the well known systems of transmission, wherein 130

it is desirable to control apparatus from some remote point by means of electromagnetic energy.

It is to be understood that the receiving and transmission systems which I have shown in Figs. 1 and 2 respectively, are merely for purposes of illustration and form no part of my invention. Furthermore, various sequences of signals may be radiated other than those indicated in the drawings by employing various spacings on the message wheel 46 and by employing various numbers of rotations of the message wheel 46 and the wave-changing switch 45 for a sequence of signals, all as will be readily understood by those versed in the art.

While I have shown only one embodiment of my invention, as hereinbefore indicated, it is capable of various changes and modifications without departing from its spirit and scope. I desire, therefore, that only such limitations shall be imposed thereon as are indicated in the appended claims.

I claim as my invention:

25 1. In a system of wireless control, a wireless transmission system comprising means for effecting the radiation of a plurality of groups of waves having different wave lengths, means for modulating each group 30 of waves in a predetermined series of impulses individual to the particular group in question, a receiving system including means for varying the tuning thereof to admit of the reception of said plurality of groups of 35 waves, and means selectively responsive to said individual series of modulations.

2. In a system of control, a central transmitting station adapted to transmit a plurality of dissimilar groups of signals, each 40 group of signals being radiated at a different wave length, and a receiving system adapted to respond only to signals of predetermined characteristics, as transmitted by the transmitting station.

45 3. In a system of control, a central transmitting station adapted to transmit a plurality of groups of dissimilar signals, said plurality of groups of signals being of different wave lengths, a receiving system and 50 a control circuit associated therewith, said control circuit being rendered effective only upon the receipt of signals of predetermined characteristics, as determined by the transmitting station.

55 4. In a system of control, a central transmitting station adapted to radiate progressively a plurality of groups of signals at different wave lengths, each group of dissimilar signals being composed of signals of 60 different predetermined durations, a receiving system, and a control circuit adapted to be rendered effective only upon the receipt of signals from said transmitting station.

65 5. In a system of control, a sending sta-

tion, means for causing said station to radiate electromagnetic energy, means including rotating members associated with said sending station for effecting the radiation of a predetermined cycle of modulated energy 70 at a plurality of wave lengths, and a receiving station having similar rotating members, means including a source of motive power for operating in synchronism with said first mentioned members, said motive-power means being normally ineffective, means responsive to the receipt of said radiated cycle of energy for rendering said motive-power means effective to rotate the rotating members of said receiving station, a local electric work circuit, and means operable upon the receipt of a complete cycle of radiated energy for energizing said local work circuit.

6. In a wireless receiving system, wave-responsive apparatus, a control circuit and a switch therefor associated with said wave-responsive apparatus, means for varying the tuning of said wave-responsive apparatus according to the wave lengths of a set of 80 signals having predetermined characteristics, whereby said switch may be rendered effective, and means for rendering said wave-responsive apparatus non-responsive and said switch non-effective upon the receipt of signals having characteristics differing from said predetermined characteristics.

7. In a remote-control apparatus, a contact device, a receiving circuit including an electromagnet adapted to open and close said contact device in accordance with received impulses of electric energy, said circuit including also a circuit making and breaking device, including a movable member, for breaking said circuit in accordance with a predetermined cycle or cycles of intervals, normally ineffective means for moving said movable member, a second circuit including an actuating magnet, a source of electric energy and said contact device for rendering said moving means effective during the energization of said actuating magnet, an auxiliary circuit making and breaking device, including a second movable member coupled to said first-mentioned movable member, for causing the energization of said actuating magnet only during the periods of interruption of said first-mentioned circuit making and breaking device, means responsive to a predetermined movement of said movable members for energizing a translating device to be remotely controlled, and means operable upon the de-energization of said actuating magnet for returning said movable members to initial position.

8. In a remote-control apparatus, a contact device, a receiving circuit including an electromagnet adapted to open and close said contact device in accordance with received impulses of electric energy, said cir-

- cuit including also a circuit making and breaking device, including a movable member, for breaking said circuit in accordance with a predetermined cycle or cycles of intervals, normally ineffective means for moving said movable member, a second circuit including an actuating magnet, a source of electric energy and said contact device for rendering said moving means effective during the energization of said actuating magnet, an auxiliary circuit making and breaking device, including a second movable member coupled to said first-mentioned movable member, for causing the energization of said actuating magnet only during the periods of interruption of said first-mentioned circuit making and breaking device, means responsive to a predetermined movement of said movable members for energizing a translating device to be remotely controlled, means operable upon the de-energization of said actuating magnet for moving said movable members backwardly to initial position, and means for preventing the energization of said actuating magnet during said backward movement.
9. In a remote-control apparatus, a receiving station having a circuit making and breaking device, including a movable member, for making and breaking a circuit in accordance with a predetermined cycle or cycles of intervals corresponding to a given signal, normally ineffective means for moving said movable member, electro-responsive actuating means for rendering said moving means effective, said circuit making and breaking device being initially in open-circuit position, a master contact device, a receiving circuit including an electro-magnet adapted to open and close said master contact device in accordance with received impulses of electric energy, means for energizing said actuating means from both said master contact device and said circuit making and breaking device, whereby said actuating means is de-energized if the received electric impulses are in such sequence as to open said master contact device during the same time that said circuit making and breaking device is in open-circuit position, means responsive to a predetermined movement of said movable member for energizing a translating device to be remotely controlled, and means operable upon the de-energization of said actuating means for returning said movable member to initial position.
10. In a remote-control apparatus, a receiving station having a circuit making and breaking device, including a movable member, for making and breaking a circuit in accordance with a predetermined cycle or cycles of intervals corresponding to a given signal, normally ineffective means for moving said movable member, electro-responsive
- actuating means for rendering said moving means effective, said circuit making and breaking device being initially in open-circuit position, a master contact device, a receiving circuit including an electro-magnet adapted to open and close said master contact device in accordance with received impulses of electric energy, means for energizing said actuating means from both said master contact device and said circuit making and breaking device, whereby said actuating means is de-energized if the received electric impulses are in such sequence as to open said master contact device during the same time that said circuit making and breaking device is in open-circuit position, means responsive to a predetermined movement of said movable member for energizing a translating device to be remotely controlled, and means operable upon the de-energization of said actuating means for moving said movable member backwardly to initial position, and means for preventing the energization of said actuating means through said contact making and breaking device during said backward movement.
11. In a remote-control system, means for transmitting intermittent electrical energy cyclicly in a predetermined manner in accordance with a plurality of frequencies, means for simultaneously interrupting said energy in accordance with a predetermined cycle or cycles of intervals corresponding to a given signal, each of said intervals being sufficiently long to include a plurality of complete waves of said intermittent electrical energy, and receiving apparatus for responding only to received impulses corresponding, both in frequency variations and in energy interruptions, to said predetermined orders.
12. In a remote-control apparatus, a receiving relay responsive only to currents of a predetermined frequency, a movable member, electro-responsive means for moving said movable member only during the receipt of a predetermined cycle or cycles of electric impulses having different durations, each of said impulses being sufficiently long to include a plurality of cycles of the received currents, means responsive to the movement of said movable member for varying the frequency to which said receiving relay responds, whereby the movement of said movable member is continued only during receipt of impulses having predetermined different durations and frequencies, and means responsive to a pre-determined movement of said movable member for energizing a translating device to be remotely controlled.
13. In a remote-control apparatus, a receiving relay responsive only to currents of a predetermined frequency, a movable member, electro-responsive means for moving

said movable member only during the receipt of a predetermined cycle or cycles of electric impulses having different durations, each of said impulses being sufficiently long to include a plurality of cycles of the received currents, means responsive to the movement of said movable member for varying the frequency to which said receiving relay responds, whereby the movement of said movable member is continued only during receipt of impulses having predeter-

mined different durations and frequencies, means responsive to a predetermined movement of said movable member for energizing a translating device to be remotely controlled, and means for restoring said movable member to initial position. 15

In testimony whereof, I have hereunto subscribed my name this 31st day of March, 1921.

ARTHUR LESLIE WILSON.
